CHEMICAL PROCESS AND PRODUCT

Alger L. Ward, Bala-Cynwyd, Pa., assignor to The United Gas Improvement Company, a corporation of Pennsylvania

No Drawing. Application June 4, 1943,
Serial No. 489,695

7 Claims. (Cl. 260—619)

This application is a continuation-in-part of my copending application Serial Number 264,591, filed March 28, 1939.

The present invention relates to the production of aryl substituted phenols. More particularly, it relates to the production of aryl substituted phenols by reacting phenols with unsaturated aromatic hydrocarbons including unsaturated aromatic hydrocarbons boiling in the range from 183° to 200° C. and obtained from light oil from the pyrolysis of petroleum oil.

The lower boiling condensate and the distillate from the tar produced in the manufacture of carburetted water gas, oil gas, and the like, which involve the pyrolysis of petroleum, is termed light oil. The higher boiling portion of the light oil contains a variety of unsaturated aromatic hydrocarbons mixed with saturated aromatic hydrocarbons of neighboring boiling points.

For instance, the higher boiling portion of a light oil produced in the manufacture of oil gas may contain styrene, ortho, para, and meta methyl styrene, indene, and other unsaturated aromatic hydrocarbons in admixture with the xylenes, cumene, pseudo-cumene, durene, and possibly other saturated aromatic hydrocarbons. These unsaturated hydrocarbons may be concentrated by further fractionation of the higher boiling portion of the light oil. For instance, a light oil produced in the manufacture of oil gas has been fractionated as follows to concentrate the following unsaturated aromatic hydrocarbons:

	Cut points, °C.
Styrene forrunnings	135 to 140
Styrene	140 to 150
Unsaturates A ₁	150 to 160
Unsaturates A ₂	160 to 167
Methyl styrene group 1	167 to 172
Methyl styrene group 2	172 to 175
Indene group	175 to 183
Unsaturates B ₁	183 to 190
Unsaturates B ₂	190 to 200

The letters A₁, A₂, B₁, and B₂, refer to unsaturated aromatic hydrocarbons or mixtures of such unsaturates, not definitely identified.

According to the present invention, unsaturated aromatic hydrocarbons including unsaturated aromatic hydrocarbons boiling in the range from 183° to 200° C. obtained from light oil from the pyrolysis of petroleum oil, are reacted with phenols in the presence of a mineral acid catalyst, under controlled temperature conditions to produce aryl substituted phenols.

The entire portion of the light oil containing aromatic unsaturated hydrocarbons and including unsaturated aromatic hydrocarbons boiling in the range from 183° to 200° C., may be reacted with phenols to give mixed aryl substituted phenols corresponding to the various aromatic unsaturates contained therein, or preferably the light oil may be fractionated to concentrate the unsaturated aromatic hydrocarbons boiling in the range from 183° to 200° C. individually or in groups and phenols reacted with the unsaturated aromatics in such fractions to give substituted phenols or groups of substituted phenols of greater or lesser purity.

For example, prior to reaction, with a phenol, the light oil of the class described may be fractionated to yield a fraction having the preponderant portion of its unsaturation in the form of unsaturated aromatic hydrocarbon material boiling in the range from 183° to 200° C. The concentration may be such as to yield a light oil fraction having its 10% and 90% boiling points within the recited range, and further the concentration may be such as to yield a light oil fraction boiling substantially completely within the recited range.

The unsaturation contained in the light oil and boiling within the range from 183° to 200° C. may be subdivided as desired and the divisions separately reacted with a phenol. For example, it may be advantageous to react a phenol with a light oil fraction, the unsaturation of which is predominantly in the form of unsaturated aromatic hydrocarbon material boiling in the range from 183° to 190° C. The concentration of this material may be such that the 10% and 90% boiling points of the fraction fall between 183° and 190° C. Further, the concentration may be such that substantially the entire fraction boils between 183° and 190° C.

Likewise a phenol may be reacted with a light oil fraction having the preponderant portion of its unsaturation in the form of unsaturated aromatic hydrocarbon material boiling in the range from 190° to 200° C. inclusive. The concentration may be such, that the 10% and 90% boiling points of this fraction fall between 190° and 200° C. Further, the concentration may be such that substantially all of the fraction boils between 190° and 200° C.

It may be desirable in the case of highly concentrated individual unsaturates or groups, to add an inert solvent such as a saturated hydrocarbon prior to reaction with the phenol.

By phenols, I intend to mean the mono and polyhydroxy derivatives of benzene and its homologues, such as for instance, phenol, cresol, resorcinol, pyrogallol, hydroquinone, pyrocatechol, naphthols, and the like, and substitution products of such compounds. As examples of acids suitable as catalysts for the reaction, sulphuric acid and phosphoric acid may be mentioned.

I have found that the aryl substituted phenols produced in the performance of my invention may be reacted with aldehydes to form resins which are soluble in drying oils, such as linseed oil and tung oil. This characteristic gives them great value for use in varnishes and lacquers in which the usual phenol aldehyde condensation products cannot be used due to their incompatibility with linseed oil and tung oil.

By aldehydes, it is intended to mean the aldehydes customarily employed in the production of phenol aldehyde condensation products of which, for example, formaldehyde and furfural may be preferred because of their relative cheapness.

I have found that in the performance of my invention, in addition to producing valuable aryl substituted phenols, the saturated aromatic hydrocarbons contained in such light oil fractions from the pyrolysis of petroleum may be recovered in a state of purity which requires little or no washing, and therefore obviates the large wash losses which arise in the washing of these saturated aromatic hydrocarbons in the presence of the unsaturates.

I have further found that by controlling the concentration of the phenol with respect to the unsaturated aromatic hydrocarbons contained in such light oil fractions, the proportion of the mono substituted aryl phenols with respect to di- and tri- substituted phenols may be controlled, increasing excesses of phenol giving higher proportions of mono-substituted products.

The invention will be further understood by reference to the following illustrative examples:

EXAMPLE 1

Six mols of phenol (564 grams) were weighed into a three necked flask equipped with a stirring device, a dropping funnel and a thermometer. To this was added 0.6 cc. of 96% H₂SO₄. To this was added 453 grams of a light oil hydrocarbon fraction obtained during a fractional distillation of light oil produced in the manufacture of oil gas by taking a cut over the temperature range 184-190° C. This hydrocarbon fraction contained 57.4% of unsaturated materials by bromine analysis (the unsaturated material being arbitrarily, for purposes of calculation, to be monoolefinic and having an average molecular weight of 130) and the weight used contained approximately 2 mols of reactive hydrocarbon material. This addition was performed dropwise with vigorous agitation. To facilitate agitation at the start of the reaction, the phenol was melted by heating it on a water bath to about 42° C.

By variation of the rate of addition of the hydrocarbon fraction, the temperature was maintained at approximately 45° C. during the entire time the hydrocarbon was being added to the phenol-catalyst mixture. The time required for this addition of hydrocarbon material was 2 to 2.5 hours.

When addition of the hydrocarbon fraction had been completed, heat was applied. The material was kept at a temperature of 130-160° C. for 2 hours. After cooling to 100° C., the sulfuric acid in the mixture was neutralized by add-

ing the calculated quantity of Na₂CO₃ dissolved in a few cc. of water.

The purification of the desired condensation product and the recovery of the excess phenol and saturated hydrocarbon was accomplished as follows:

Without further washing or other treatment, the reaction mixture was distilled. After distilling over about 591 grams of unreacted phenol and saturated hydrocarbons, a fraction was taken distilling over in the range 155-200° C. at 4-6 mm. absolute pressure, which weighed 288 grams, about 64% of theory. This fraction was a viscous, oily liquid, phenolic in nature as shown by subsequent tests. A solid residue remained in the distillation flask.

The excess phenol may be separated from the unreacted hydrocarbon by known methods.

The material distilling over in the 155-200° C. range at 4 to 6 mm. pressure, had the following physical properties.

Color (Gardner-Holdt)	5
Sp. gr. D 20/4	1.0748
N 20/D	1.5872
25 Mol. weight	196.9
Zerewitinoff value	per cent 85.4

This phenolic material evidently comprises a mixture of aryl substituted phenols, produced by reaction of the phenol with the aromatic unsaturates of this light oil cut.

EXAMPLE 2

12 mols of phenol (1128 grams) were weighed into a 3 necked flask equipped with a stirring device, a dropping funnel and a thermometer. To this was added 1.2 cc. of 96% H₂SO₄. To this was added 769 grams of a light oil hydrocarbon fraction obtained during a fractional distillation of a light oil produced in the manufacture of oil gas by taking a cut over the temperature range 190-200° C. This hydrocarbon fraction contained 67.6% of unsaturated materials by bromine analysis (the unsaturated material being arbitrarily calculated as mono-olefinic and having an average molecular weight of 130) and the weight used contained therefore about 4 mols of reactive hydrocarbon material. This addition was performed dropwise with vigorous agitation. To facilitate agitation at the start of the reaction, the phenol was melted by heating it on a water bath to about 42° C.

By variation of the rate of addition of the hydrocarbon fraction, the temperature was maintained at approximately 45° C. during the entire time the hydrocarbon was being added to the phenol-catalyst mixture. The time required for this addition was 6-7 hours.

When the addition of the hydrocarbon fraction had been completed, heat was applied. The material was kept at a temperature of 130-160° C. for 2 hours. After cooling to 100° C., the sulfuric acid in the mixture was neutralized by adding the calculated quantity of Na₂CO₃ dissolved in a few cc. of water.

The purification of the desired condensation product and the recovery of the excess phenol and saturated hydrocarbon was accomplished as follows:

Without further washing or other treatment, the reaction mixture was distilled. After collecting about 1013 grams of unreacted phenol and saturated hydrocarbons, a fraction was taken distilling over in the range of 160-200° C. at 4-6

mm. absolute pressure, which weighed 569 grams, about 63% of theory.

This fraction was a viscous, oily liquid, phenolic in nature as shown by subsequent tests. A solid residue (236 grams) remained. This residue quite probably has value from its resinous properties.

The non-reacted hydrocarbon may be separated from the unreacted phenol by conducting a fractional distillation.

The material distilling over in the range 160-200° C. at 4 to 6 mm. absolute pressure, had the following physical properties:

Color (Gardner-Holdt)	7
Sp. gr. D 20/4	1.0636
N 20/D	1.5830
Mol. weight	195
Zerewitinoff value	percent 85

This phenolic material evidently comprises a mixture of aryl substituted phenols produced by reaction of the phenol with the aromatic unsaturates in this light oil cut.

Referring to Examples 1 and 2 the following table gives properties of the distillation residues produced therein.

Table

Example	Description of unsaturates	Grams residue per mol.	2-5 mm. absolute pressure initial dist. point	Other properties
1.	B-1	24	° C. 200	Dark, resinous, tacky, solid.
2.	B-2	59	200	Do.

Distillation of these residues gives very viscous semi-solid liquids of deep amber color constituting di-substituted phenols.

As before stated, the proportion of mono-substituted phenols to di-substituted and tri-substituted phenols produced in the reaction may be controlled by controlling the proportion of phenol to the unsaturated aromatic hydrocarbons, a molar excess of phenol having been found desirable when the desired products are mono substituted phenols. However, the excess of phenol may be limited by practical considerations and it may be desirable to employ proportions resulting in the production of considerable proportions of both mono and di-substituted products.

For example, a molar ratio of phenol to fraction unsaturation (considered arbitrarily for purposes of calculation as mono-olefinic material of average molecular weight of 130) of 5 to 1 may result in the production of mono and di-substituted products in a ratio of the order of 10 to 1. On the other hand, a molar ratio of phenol to fraction unsaturation of 1 to 1 (calculated as above) may produce mono and di-substituted products in a ratio of less than 2 to 1.

Thus varying proportions of mono and di-substituted phenols may be secured by varying the ratio of the quantities of the respective reactants employed.

EXAMPLE 3

To two mols of phenol containing 0.2% by weight of H_2SO_4 is added slowly 1 mol of aromatic hydrocarbon unsaturation boiling preponderantly between 183° and 200° C. (calculated arbitrarily as mono-olefinic and of average molecular weight of 130) and contained in a light oil fraction obtained in the pyrolysis of petroleum oil. The tempera-

ture is kept below 50° C. by regulation of the rate of addition. When the light oil fraction is all added the mass is heated to 120-150° C. for 2 hours with agitation. After neutralization of the H_2SO_4 with the calculated amount of Na_2CO_3 solution, the product is fractionally distilled. The fraction distilling above 200° C. will be found to contain the di-substituted phenol material.

It will be seen from the examples given above, that the process of the invention provides a simple and inexpensive separation of the products of the reaction.

After neutralization of the small quantity of acid, it is only necessary to distill the products to recover separately the water, the unreacted phenol and hydrocarbons, and to separate the mono-aryl phenol from di-aryl phenols and any higher substitution products, which are less valuable products. It is not necessary to wash out the acid catalyst prior to distillation because of the small quantity employed. The unreacted hydrocarbon material and unreacted phenol may be readily separated by known means.

The procedure permits the separate recovery 25 of the saturated aromatic hydrocarbons of these light oil fractions obtained in the pyrolysis of petroleum, which contain considerable concentrations of aromatic unsaturates without the large wash losses incident to washing out the aromatic 30 unsaturates and further provides for recovering the aromatic unsaturates as valuable aryl phenols.

For example, in the production of aryl substituted phenols from the light oil unsaturation in the boiling range from 183° to 200° C., recoveries of saturated aromatic hydrocarbons containing little or no olefinic contamination are possible by fractional distillation of the product followed by separation of the unreacted phenol and the unreacted hydrocarbons.

40 As stated before, the aryl phenols produced in accordance with the present invention may be reacted with aldehydes to produce substituted phenol-aldehyde resins which are compatible with drying oils, such as linseed oil and tung oil.

EXAMPLE 4

In a laboratory preparation of a varnish resin approximately 280 grams of the mono-substituted product phenol made from about 160 to 200° C. at 2-5 mm. pressure are used. This is equivalent to 50 1 1/4 mols on the assumed average molecular weight of 130 for the original unsaturates. The phenol is reacted with 2 1/2 mols (75 grams) of formaldehyde which is used in the form of an approximately 37% aqueous solution. The phenol and formaldehyde, together with two grams of oxalic acid are agitated in a flask provided with a reflux condenser at reflux temperature for approximately 24 hours. The formaldehyde is added step-wise; one-half being added initially, one-quarter after eight hours and one-quarter after sixteen hours. At the expiration of the heating period the reflux condenser is removed and the resin is steamed for about two hours at approximately 60 200° C. and 50 mm. pressure. The steam is discontinued but the vacuum is left on the system to remove any small quantity of moisture present. The resin is poured out of the flask while still molten, and allowed to cool. The hardened resin is crushed and sieved.

The resin will be found compatible with linseed and tung oils and may be cooked with these and other drying oils to form varnishes.

The compatibility of these resins with the usually employed drying oils, linseed oil and tung

oil, is an extremely valuable characteristic. It opens the door to the employment of phenol aldehyde condensation products in coating compositions, such as drying oil varnishes, and affords a new utilization for the unsaturated aromatic hydrocarbons contained in light oil from petroleum pyrolysis, of which there is an extremely large potential supply.

The process herein described also affords a more economical method of recovering the saturated aromatic hydrocarbons accompanying the unsaturated aromatic hydrocarbons in such light oil.

It is to be understood that the above particular description is by way of illustration and that changes, omissions, additions, substitutions, and/or modifications may be made within the scope of the claims without departing from the spirit of the invention which is intended to be limited only as required by the prior art.

I claim:

1. A process comprising reacting a phenol with a light oil fraction containing unsaturated hydrocarbon material boiling within the range from 183° to 200° C., said reaction taking place in the presence of a condensation catalyst, and said light oil having been obtained from products of pyrolysis of petroleum oil.

2. A process comprising condensing a phenol in the presence of a mineral acid catalyst with a light oil fraction containing unsaturated aromatic hydrocarbon material which boils in the range from 183° to 200° C., said light oil having been obtained from products of pyrolysis produced in the manufacture of combustible gas by a process involving the thermal decomposition of petroleum oil.

3. A process for producing aryl substituted phenol material comprising reacting a phenol in the presence of a mineral acid catalyst with a

light oil fraction boiling preponderantly in the range from 183° to 200° C. and containing unsaturated aromatic hydrocarbon material boiling within said range, said light oil having been separated from products of pyrolysis obtained in combustible gas manufacture involving the thermal decomposition of petroleum oil.

4. A process for producing aryl substituted phenol material comprising reacting phenol in the presence of a mineral acid catalyst with a light oil fraction having 10% and 90% boiling points within the range from 183° to 200° C. and containing aromatic unsaturation boiling within said range, said light oil having been recovered from petroleum pyrolysis products.

5. A process for producing aryl phenol material comprising condensing a phenol in the presence of a mineral acid catalyst with a light oil fraction boiling preponderantly within the range from 183° to 190° C. and containing aromatic unsaturation boiling in said range, said light oil having been obtained from products of petroleum oil pyrolysis.

6. A process for producing aryl phenol material comprising condensing a phenol with a light oil fraction the preponderant part of which boils in the range 190° to 200° C. and which contains aromatic unsaturation which boils within said range, said light oil having been obtained from products of pyrolysis of petroleum oil.

7. A process for producing aryl phenol material comprising condensing phenol in the presence of sulfuric acid as a catalyst with a fraction of a light oil obtained from petroleum oil pyrolysis products, said fraction containing unsaturated aromatic hydrocarbon material which boils within the range from 183° to 200° C., said condensation being effected under temperature conditions of from approximately 120° C. to approximately 160° C.

ALGER L. WARD.
